DISPLAY STANDS AND CONTAINERS FOR ARTICLES

Malcolm Laughton, Selly Oak, Birmingham, England, assignor to Foster Grant Company Incorporated, Leominster, Mass.

Application March 3, 1958, Serial No. 718,530

Claims priority, application Great Britain March 26, 1957

2 Claims. (Cl. 211—49)

The invention relates to display stands and storage containers or holders for articles for use for example on shop counters or works store counters.

Many articles are displayed in shops in holders and stands where they can be readily seen and examined and easily removed for sale or other reasons. If a number of articles are arranged in a stand or holder one behind another in a vertical or inclined position, the removal of one or more of them may leave the remainder loose and liable to be disarranged in the stand or holder, or in a compartment thereof where the stand or holder is partitioned to take a number of groups of articles.

It is an object of the present invention to provide a multiple compartment display stand or holder with the compartments side by side and closed, when no articles are in place, by a flap which flap is hinged by a bent lip over an edge at the rear of the stand and urged into a position to engage articles in the compartment by a tension spring connected to the lip.

A convenient embodiment of the invention is to hinge a curved flap to a back wall, or a bar across the back of each compartment of a holder. The flap may be hinged at its upper part in the manner hereinbefore referred to and is loaded by a tension spring arranged to move the lower part of the flap forwardly around the hinge axis. In this construction the flap is preferably curved near its lower end in a rearward direction relatively to its supporting surface so that as the latter moves in a curved path, forwardly and upwardly, it does not present an edge but a smooth pressure surface against the article at the back of a group.

In the appended drawings,

Figure 1 is a front view of a stand or holder with a number of compartments.

Figure 2 is a rear view of the stand or holder shown in Figure 1.

Figure 3 is a vertical section on line 4—4 of Figure 1.

The construction shown in the drawings comprises a front wall *a*, side or end walls *c*, base or floor *d*, and a bar *g* across the back. The front wall *a* is preferably lower than the back bar and one end of the wall is preferably lower than the other, the upper edge of the low front wall being curved or inclined downwardly to join the lower of the side walls *c* at a point well below the upper edge of the latter. The upper edge of the back bar *g* is stepped down in a series of shallow steps *h* to the upper edge of the lower side wall. Division bars or forwardly extending walls *i* or complete partitions divide the interior of the stand into a series of compartments, the upper edge of each division bar or partition *i* rising from the front to the back, see Figure 3. In each of the compartments formed by the division bars or partitions *i* a hinged flap or closure *j* is mounted. Each flap is made with a lip *k* or flange perpendicular to the remainder of the flap or inclined at a considerable angle to the flap, and the flap is hinged or pivoted by arranging the lip *k* or flange to overhang the upper edge of the back bar or wall *g*. A tension spring *l* is connected to the lip

2

or flange and the spring is suitably anchored at its other end to the back bar *g* as shown at *m* or to the base *d* as shown at *n*. As the flap *j* is pressed down, the tension of the spring is increased and the spring loading retains the flap in contact with the rearmost article of a group in the compartment and supports them in upright position. When no articles are in front of it, the flap moves into light contact with the inside face of the front wall as shown in Figure 3. Each flap *j* is curved rearwardly in its lower part as at *o* for the purpose hereinbefore mentioned. The tension springs may be rubber loops *p*.

The stand is convenient for use with a number of articles such as combs, small rules or scales, rows of pencils, or other articles, the length of which is large in relation to the thickness of the article so that a number of the articles can be inserted one behind the other in the compartments and will be kept in a position in which the upper part of the article is displayed but the articles are retained in ordered position and are not disturbed as individual articles are removed for sale or inspection. Further, articles may be returned to the pile by simply pushing them down into the compartment, most conveniently down the front of the flap behind any other articles already in the compartment. The stand or holder can be conveniently made of moulded plastic, light metal or other materials.

I claim:

1. A display stand and holder for articles comprising a floor, a front wall united to end walls and to the floor, and a back bar having forwardly extending walls projecting from it at spaced intervals, the forward ends of said forwardly extending walls being united to the front wall to divide the stand and holder into a series of compartments; a unitary closure flap for each compartment of the series, each flap being of a width substantially that of the compartment, extending over and supported by the back bar between adjacent walls and having a downwardly extending lip rearwardly of the bar and a downwardly extending front end, each flap being spring loaded by a tension spring one end of which is connected to the lower end of the lip and the other end thereof anchored to a fixed part of the stand, the downwardly extending front end of each flap abutting the inner surface of the front wall when its compartment is empty and bearing against and supporting articles by pressure thereon when articles are inserted in its compartment in such manner that articles can be stored one behind the other in displayed condition in each compartment and withdrawn therefrom for inspection and sale and also returned thereto.

2. A display stand and holder in accordance with claim 1 in which the downwardly extending front end of the flap is connected to the body of the flap by a curved portion so that as the flap moves forwardly and upwardly as an article is withdrawn it presents a smooth pressure surface against an article, and permits the front end to bear against the front of the compartment so that the flap forms a readily yielding closure for the compartment when no article is therein and in a manner to provide a downward lead for the insertion of articles into the compartment.
